TOBACCO STEMMING MACHINE

Thomas E. Pasley, Roanoke, Va., assignor, by direct and mesne assignments, to Comas Cigarette Machine Company, Salem, Va., a corporation of Virginia

Application June 30, 1931, Serial No. 547,979
Renewed August 17, 1933

43 Claims. (Cl. 131—57)

My invention relates to tobacco stemming machines.

In accordance with my invention I provide a tobacco stemming machine wherein the tobacco leaves may be fed continuously to stem butting means, in the form of a layer or layers of leaves, for stripping the blade from the butt of the stem. After this action, the layer or layers of tobacco leaves thus treated are fed to the stripping means, which strips the remainder of the blades from the stem. The stripping means thus acts upon a layer or layers of the tobacco leaves, or a continuously traveling plurality of tobacco leaves, to strip the same, as distinguished from the individual stripping of each leaf. The layer or layers of tobacco leaves are fed through the butt stemming means and delivered therefrom to the stemming means in a continuous manner, whereby the output of the machine is greatly increased. The machine is relatively simple in construction, cheap to manufacture and reliable in operation.

The stem butting means and the stripping means, each preferably embody a pair of endless structures carrying stripping elements, preferably in the form of carding or stripping brushes, which are spaced, are relatively short with relation to the length of the endless structures, and hence afford vacant spaces on the endless structures. The stripping brushes on each pair of endless structures are so timed in operation that the corresponding brushes of the endless structures come together, during the travel of the endless structures, for effecting the stripping action.

The machine is provided with leaf-feeding means for coaction with the stem butting means, and leaf-feeding means for coaction with the stripping means, the arrangement being such that the stem butting leaf-feeding means positively delivers the leaves to the feeding means of the stripping means. The feeding means is of a peculiar construction for coaction with the stem butting means and the stripping means. Such feeding means embodies pairs of endless devices arranged in superposed relation for receiving layer or layers of tobacco leaves between the same. These endless devices are adapted for positive binding engagement with the leaves to not only effect their feeding movement but to prevent the longitudinal displacement of the leaves by the action of the stem butting means and the stripping means. The feeding means preferably embodies rolling elements arranged between its coacting parts to reduce the friction

to the minimum and economize in power for driving the machine.

Means are provided to accurately regulate the tension of the endless structures of the stem butting means and of the stripping means, and to properly force the upper endless structure toward the lower endless structure. Means are also provided to accurately vertically or angularly adjust the lower run of the endless structure in the stripping means with relation to the upper run of the endless structure.

Means are provided to clean the brushes carried by the endless structures, and this cleaning means is preferably driven from the tension regulating means.

The invention also resides in the combination and arrangement of parts as set forth in the claims.

The present application is a continuation in part of my co-pending application for Tobacco Stemming machine, filed May 10th, 1929, Serial Number 361,937.

In the accompanying drawings forming a part of this specification, and in which like numerals are employed to designate like parts throughout the same,

- 10 In the drawings, wherein for the purpose of illustration is shown a preferred embodiment of my invention, the numeral 20 designates a table top, supported by legs 21. Mounted upon the table top are stripping mechanism 22 and butt 15 stemming mechanism 23, which are identical in all substantial respects, whereby a detail description of one will suffice for both. These mechanisms extend inwardly from opposite sides of the table top, as shown. Each of these mechanisms 22 and 23, see more particularly Figures 5, 20 6 and 8, embodies a lower endless structure including a pair of spaced sprocket chains 24, having their inner ends passing about sprocket wheels 25, rotatably mounted upon a transverse 25 shaft 26 supported in suitable stationary bearings attached to the table top. The outer ends of this pair of sprocket chains 24 pass about sprocket wheels 27, which are rigidly mounted upon a shaft 28. The sprocket chains 24 pass through suitable openings in the table top 20 so that their upper runs travel in slidable contact with the upper surface of the table top and, therefore, travel in the same plane and are rigidly held against downward flexing movement. The lower runs 30 of the sprocket chains 24 are engaged by sprocket wheels 29, rigidly mounted upon a transverse shaft 30, rotatably mounted upon angularly adjustable arms 31. The arms 31 are rigidly mounted upon a rock shaft 32, journaled in bearings formed 35 upon stationary arms or brackets 33. An adjusting element or screw 34 has screw-threaded engagement with a lug 35, rigidly carried by the arm or bracket 33, and is arranged to engage behind one arm 31. By advancing the adjusting screw 34, it is obvious that the rock shaft 32 will be turned and the sprocket wheels 29 shifted downwardly into firmer engagement with the lower runs of the sprocket chains 24, thereby regulating the tension of these sprocket chains. 40
- 50 It is obvious that the arms 31 and associated elements constitute a tension regulating device for co-action with the sprocket chains 24. This device also serves as a power transmitting means, as will be further described.
- 55 Each mechanism 22 and 23 also embodies an upper endless structure, including sprocket chains 35, engaging at their inner ends, sprocket wheels 36, rotatably mounted upon a shaft 37. This shaft is preferably rigidly attached to the inner 60 ends of side members 38, included in a vertically swinging or adjustable support. The outer ends of the side members are pivotally mounted upon a shaft 39, and this shaft is journaled in fixed bearings 40. The sprocket chains 35, at their 65 outer ends, pass about sprocket wheels 41, rigidly mounted upon the shaft 39. Rigidly connected to the outer ends of the side members, and preferably formed integral therewith, is an upstanding yoke 42, arranged outwardly of and near a stationary upstanding yoke 43, preferably formed integral with the bearings 40. Adjustable means are provided to move the yoke 42 toward and from the stationary yoke 43, and to lock the same in a selected adjusted position. This adjusting means 70 preferably embodies a bolt 44, having screw-
- 75

threaded engagement within an opening formed in the yoke 43, and slidably mounted within an opening 45, formed in the movable yoke 42. The bolt is non-rotatable in operation and carries nuts 46 disposed upon opposite sides of the adjustable yoke 42. It is obvious that these nuts may be manipulated to adjust the yoke 42 toward and from the yoke 43. Tension regulating means are provided for co-action with the sprocket chains 35, comprising sprocket wheels 47, which are rigidly mounted upon a transverse shaft 48, rotatably mounted upon bearings formed upon the ends of angularly adjustable arms 49. These arms are rigidly mounted upon a rock shaft 50, journaled through suitable bearings in the side members 38, so that they turn with the rock shaft. One arm 49 is provided with an extension 51, to be engaged by adjusting bolt 52, having screw-threaded engagement with a lug 53, rigidly carried by one side member 38. It is thus seen that by manipulating the bolt 52, the sprocket wheels 47 may be moved upwardly to increase the tension upon the sprocket chains 35. This tension regulating device also serves as a power transmitting device, as will be explained.

As clearly shown in Figures 5 and 6, the lower runs of the sprocket chains 35 travel in spaced relation above the upper runs of the sprocket chains 24, and these two sets of sprocket chains are co-extensive in length. The mechanism 22, 105 preferably, embodies a flat pressure plate 54, which is arranged between the side members 38, and is provided at its inner end with U-bolts 55, pivoted upon a transverse shaft 56, rigidly connected with the side members 38. The outer end 110 of the pressure plate 54 is provided with operating brackets 57, rigidly attached thereto, and cams 58 are arranged between these brackets and the upper surface of the pressure plate 54, for raising and lowering the outer end of the pressure plate. 115 These cams are rigidly mounted upon a rock shaft 59, journaled in bearings formed in the side members 38, and the rock shaft 59 is turned by means of a nut 60, or the like, which may be engaged by a suitable tool, the rock shaft 59 having suitable 120 frictional engagement within its bearings, so that it will remain in the adjusted position. The mechanism 23 is not shown as embodying pressure plate 54, which I have found to be unnecessary, but the pressure plate may be used in connection with the mechanism 23, if desired.

Each pair of sprocket chains 24 and 35 carry transverse stripping elements 61, preferably in the form of wire brushes. As more clearly shown in Figures 9 to 11, inclusive, each brush embodies 130 a back 62, carrying wire teeth 63. These wire teeth are suitably stiff and resilient and their outer ends are angularly bent, as shown. The back 62 is arranged upon a rigid strip 64, and has clamping engagement with side members 65, detachably connected with the rigid strip or base 64, by screws 66, or the like. The rigid strip 64 extends beyond the ends of the sides 65, and is rigidly connected with angle-irons 67, by means of bolts 68, and each angle-iron is connected with 135 an adjacent pair of pivots 69, included in the sprocket chain. It is thus seen that the brush element may be easily removed from the strip or support 64, for repair or replacement, and that the brush element travels with its pair of sprocket 140 chains, without turning upon its longitudinal axis with relation to these sprocket chains. The brush elements 61 in each set are preferably equidistantly spaced, and the brush elements in one set are spaced the same distances as the brush 145

elements in the other set, so that each brush element in one set is adapted to be brought into a position directly opposite the brush element of the other set, such brush elements being superposed, 5 as clearly shown in Figure 5. In order that the sets of sprocket chains 24 and 35 may travel in unison, the shafts 39 and 28 are positively geared together, and for this purpose a pinion 70 is rigidly mounted upon the lower shaft 28 in permanent 10 engagement with a pinion 71, rigidly mounted upon the upper shaft 39. Means are provided to clean the brush elements 61, carried by the sprocket chains 35, including a rotary brush 72, rigidly mounted upon a shaft 73, rotatable within 15 bearings formed upon arms 74, rigidly connected with the side members 38. The shaft 73 is provided at one end with a smaller sprocket wheel 75, engaged by sprocket chain 76, extending inwardly to engage a larger sprocket wheel 77, rigidly 20 mounted upon the shaft 48. Means are also provided to clean the brush element 61, carried by the sprocket chains 24, comprising a rotary brush 78, rigidly mounted upon a rotary shaft 79, journaled in suitable stationary bearings. This shaft 25 79 is provided at one end with a smaller sprocket wheel 80, engaged by an inwardly extending sprocket chain 81, engaging a larger sprocket wheel 82, rigidly mounted upon the shaft 30. The sprocket chains 76 and 81 are sufficiently slack so 30 that they do not interfere with the adjustment of the tension regulating devices for controlling the tension of the sprocket chains 24 and 35.

The numeral 83 designates leaf feeding means extending transversely of and adjacent to the intake end of the stripping mechanism 22, and the numeral 84 designates leaf feeding means arranged in a similar relation to the stem butting mechanism 23. These feeding means are identical in all substantial respects. Each leaf feeding 35 means embodies upper and lower endless structures 115 and 116. These endless structures are identical in some respects, and the portions of the same which are identical will be described in connection with both of them. Each of the upper 40 and lower endless structures embodies a pair of pulleys 117, each pulley being provided in its periphery with an annular groove 118 and having sides 118'. The sides of each groove pulley are provided with sets of sprocket teeth 119. Each 45 pulley is, therefore, a combined grooved pulley and sprocket wheel. Each endless structure further embodies an endless plate belt 120, and each plate belt is formed of a plurality of rigid metal plates 121, see Figure 16, having interfitting 50 knuckles 122 and 123, pivotally connected by pins 124. Each plate is provided upon its outer side with a pair of grooves 125, which, when the metal plates are assembled into the endless plate belt, constitute continuous endless grooves. As more 55 clearly shown in Figure 16, the pins 124 carry on their ends, rollers 126 and these rollers are arranged to mesh with the sprocket wheel teeth 119, the interfitting knuckles 122 and 123 of the several plates operating between the sides 118' of 60 the grooved pulley. Each endless structure further embodies a roller chain, embodying a pair of endless chains 127, formed of a plurality of links 128 connected by pins 129, these pins rotatably carrying rollers 130, projecting beyond the 65 edges of the links for a slight distance, as shown. These roller chains travel within the grooves of the pulleys 117, and there is sufficient slack in the roller chains so that they need not be positively driven by the pulleys but can partake of movement 70 with relation thereto, although they travel 75

generally with the endless plate belt. The knuckles 122 and 123 of the plates of the endless plate belt traveling within the grooves 118 of the pulleys 117, travel upon the rollers 130. The grooved pulleys 117 of the upper endless structure 80 115 of the feeding means 84 are mounted upon and have rotation with shafts 130 and 131, while the grooved pulleys 117 of the lower endless structure are mounted upon and have rotation with shafts 132 and 133. The shafts 130 and 131 are mounted upon a frame 134, arranged above the table top 20, and pivoted upon a shaft 135, to partake of slight vertical swinging movement, caused by the varying thicknesses of the tobacco leaves fed between the endless structures 115 and 90 116. The lower shafts 132 and 133 are mounted in fixed bearings 135'. The shafts 131 and 133 have engaging pinions 136, so that the shafts turn at the same speed and in opposite directions, with the result that the adjacent upper and lower runs 95 of the endless structures travel in the same direction and at the same speed. The means employed to drive the lower shaft 133 will be described later. The upper pair of pulleys 117 of the feeding means 83 are mounted upon shafts 130' and 131' 100 carried by the frame 134. The lower pair of pulleys 117 of the feeding means 83 are rigidly mounted upon shafts 132' and 133', journaled in fixed bearings secured to the table or frame. The pinions 136 are rigidly secured to the shafts 130' 105 and 132', to cause them to rotate in unison and in opposite directions.

Arranged between the upper and lower runs of the endless roller chain 127, of each upper endless structure 115, is a stationary pressure guide 110 138, rigidly mounted upon the frame 134, and having its edge provided with a groove 139, Figure 13, receiving the lower run of the endless roller chain. This pressure guide serves to guide the roller chain in its travel and also serves to 115 limit the upward movement of the same. Arranged between the runs of the roller chain 127 of each lower endless structure 116 is a stationary pressure guide 140 which is fixed upon the table. This pressure guide is provided at its upper edge 120 with a horizontal groove 141, receiving the upper run of the roller chain, for guiding the same during its travel, and to limit the downward movement of such run. The guide 140 is mounted upon an arched base 142 having a passage 143, for 125 the travel of the lower run of the endless structure 116.

Each upper endless structure 115 further embodies a pair of endless belts 144, preferably formed of rubber, having a reinforcing fabric 130 backing. These rubber belts are held within the grooves 125 of the plates 121. Each lower endless structure 116 embodies a pair of endless belts 145, preferably formed of leather, and these endless belts 145 operate within the grooves 125 of 135 the plates. In view of the foregoing description, it will be seen that the lower and upper runs of the endless structures 115 and 116 are brought together, and the belts 144 and 145 travel in close relation, in substantial parallel planes. The 140 endless plate belts, roller chains, and pressure guides serve as positive means for holding the adjacent runs of the endless structures against lateral displacement. The rubber belts 144 are capable of some degree of yielding action, and 145 when a layer of tobacco leaves, being fed between the endless structures, increases in thickness, within limits, the upper endless structure may rise slightly, due to the pivotal mounting of the frame 134. It is necessary that the means for 150

feeding the tobacco leaves to the stripping means to exert substantial pressure upon the leaves to not only feed them, but to hold them against longitudinal movement due to the pulling action of the stripping means. As a result of this, difficulty may be experienced in properly driving the endless structure were it not for the presence of the free roller chains, which I have found permits of the driving of these endless structures without excessive friction, which would consume too much power. These endless roller chains permit of the endless structures being driven quietly and with the minimum friction and the minimum power.

15 The feeding means 84, after passing the leaves through the butt stemming means, positively delivers the leaves to the feeding means 83 of the stripping mechanism 22. This is accomplished by having the adjacent inner ends of the feeding means 83 and 84 overlapping, the adjacent pulleys 117 having their shafts in alignment. I have found that the stripping means 22 will strip the leaves from the stem throughout the entire length of the stem, without breaking the stem to any considerable extent. This is a feature which is highly desirable to manufacturers of some types of cigarettes, where it is not desired to have any appreciable amount of the stem in the cigarette. However, some manufacturers wish to use some of the stem in the cigarette, particularly the small end of the stem. To meet this condition, I provide means arranged at the feeding means of the butt stemming mechanism to score or weaken the leaf near its reduced or free end, so that the forward or reduced end of the stem will break when the leaf is subjected to the stripping action of the brushes within the stripping mechanism.

40 This scoring means embodies an upper scoring disc 146, rigidly mounted upon an upper horizontal shaft 147, journaled in the ends of an inverted U-shaped frame 148, pivotally supported at one end by a shaft 149, journaled in bearings 150. This frame is engaged by an adjusting bolt 151, and may be urged downwardly by this bolt, which also serves to limit its upward movement. Extending through an opening in the table top 20 is a co-acting scoring disc 152, arranged near and opposite the scoring disc 146, and rigidly mounted upon a rotatable shaft 153, journaled in bearings 154. These shafts are rotated in the same direction and at the same speed and in the direction of travel of the endless structures 115 and 116. The upper shaft 147 receives its rotation from a pulley 155, rigidly mounted thereon, driven by a belt 156, engaging a pulley 157, mounted upon the shaft 131. The lower shaft 153 is equipped with a pulley 158, driven by a belt 159, driven by a pulley 160, mounted upon the shaft 133. The edges of the peripheries of the scoring discs 146 and 152 are blunt, so that they will not cut the leaves or stems, but will score or weaken them, so that the free ends of the stems will readily break off when subjected to the action of the endless stripping elements.

45 The feeding means 84 is slightly different from the feeding means 83, inasmuch as the lower belts 145 do not terminate with the upper pulleys 117, and while passing about these pulleys they are extended a substantial distance beyond the same, and engage about a grooved pulley 161, rigidly mounted upon a rotatable shaft 162. The upper runs of these belts 145 travel upon the upper surface of the table top 20 and serve to feed the tobacco leaves to the feeding means 84, proper-

In order that these belts 145 may more properly conduct the leaves to the feeding means, they are aided by a belt 163, the upper run of which travels upon the upper surface of the table top 20, and this auxiliary belt 163 engages a grooved pulley 164, rigidly mounted upon the shaft 162. The opposite end of the belt 163 engages a grooved pulley 165, which is rigidly mounted upon the shaft 132.

50 Means are preferably provided for exerting a downward pull upon the swinging frame 134 of the feeding means 83, comprising eye-bolts 166, passing through openings formed in brackets 167, rigidly attached to the frame 134, and carrying adjustable thumb nuts 168. The lower ends of these eye-bolts are connected with retractile coil springs 169, attached at their lower ends to a stationary part of the frame.

55 The frame 134 of the feeding means 84 is forced downwardly by a U-shaped pressure frame 170, the forward ends of which engage the top of the frame 134. At its closed end, the pressure frame has a knuckle 171, pivotally mounted upon the shaft 135, and this knuckle has an extension 172 to be engaged by an adjusting bolt 173, adjustably connected with a stationary part of the frame. The pressure frame 170, therefore, serves to force the frame 134 downwardly and to limit its upward movement.

60 The numeral 174 designates a motor which drives the shaft 132' through suitable reduction gearing 176. This shaft 132' extends to the opposite side of the machine. The lower pinion 136 of the feeding means 83 is rigidly mounted upon this shaft 132'. The shaft 132' is provided at its opposite end with a sprocket wheel 177, driving a sprocket chain 178, engaging a sprocket wheel 179, which is rigidly mounted upon the shaft 133 of the feeding means 84. The stripping mechanism 22 is driven by a bevel gear 180, rigidly connected with the lower pinion 70, and this bevel gear is driven by a bevel gearing 181, rigidly mounted upon the shaft 132'. The butt stemming mechanism 23 is driven by a shaft 182, which is connected with the lower pinion 70. This shaft is journaled in stationary bearings 183, and carries a bevel gear 184, driven by a bevel gear 185, rigidly mounted upon the shaft 132'.

65 The operation of the machine is as follows:

70 The feed mechanism 84 and the feed mechanism 83 are continuously driven at substantially the same speed, and their inner runs travel from left to right, as more clearly shown in Figure 7. The adjacent ends of these feed mechanisms overlap and hence the feed mechanism 84 positively delivers the leaves to the feed mechanism 83. The tobacco leaves are placed upon the table top 20 and are distributed in suitable layer or layers upon the extension of the belts 145 and the belt 163, with their butt ends facing the butt stemming mechanism 23. These leaves are carried between the endless structures of the feeding mechanism 84, with their butt ends projecting suitable distances beyond the same. The butt stemming means 23 is continuously driven and its endless brush carrying elements travel in unison with their inner runs traveling from the feeding means 84. The stripping brushes 61 of the butt stemming mechanism are brought together in pairs, engaging above and below the butt ends of the leaves, thereby removing the leaf from the stem. The stripping brushes having resilient teeth or bristles possess some yielding action so that they will properly remove the leaf from the stem without breaking the stems, 150

to any considerable extent. The leaves with their butt ends thus stripped, are now transferred in a positive manner, to the feeding mechanism 83, which securely holds the stripped butt end portions of the leaves and feeds or advances these leaves through the stripping means 22. The stripping means embodies the endless devices having the stripping brushes, and these brushes are brought together in pairs to engage above and below the leaves and strip the blade from the stems throughout the entire length of the stems. The stripping action of the blades from the stem is a delicate operation and frequently requires a fine adjustment of the pressure that the brushes exert upon the leaves. This pressure may have to be varied depending upon the grade, character or condition of the tobacco leaves. It is frequently necessary to gradually reduce the pressure as the free end of the leaf is approached as the stem tapers toward the free end of the leaf. Accurate adjustment of the pressure between the brushes and the leaf may be effected in my machine, as more clearly shown in Figures 5 and 6. By angularly adjusting the support 38, the brushes engaging the leaves near their butt ends may engage with the desired pressure, and this pressure gradually decreases in a direction from these butt ends. By adjusting the pressure plate 54 independently of the support 38, the decreasing pressure may be accurately regulated. The completely stripped stems discharge from the right end of the feeding mechanism 83, while the blades from the butt ends of the stems discharge from the outlet end of the butt stemming means 23, and the blades from the remaining portions of the stems discharge from the discharge end of the stripping means 22.

It is to be understood that the form of my invention herewith shown and described is to be taken as a preferred example of the same and that various changes in the shape, size, and arrangement of parts may be resorted to without departing from the spirit of my invention or the scope of the subjoined claims.

Having thus described my invention, what I claim is:

1. In a tobacco stemming machine, stripping means, and leaf-feeding means arranged near and cooperating with the stripping means, said leaf-feeding means comprising a lower endless belt, rollers arranged beneath the upper run of the belt, a vertically movable pressure support arranged near and above the lower endless belt, an upper endless belt carried by the pressure support and arranged near and above the lower endless belt, and rollers carried by the pressure support and engaging the lower run of the upper belt.

2. In a tobacco stemming machine, feeding means comprising a lower endless belt, rollers disposed beneath the upper run of the lower belt, a vertically movable pressure support arranged near and above the lower belt, an upper endless belt carried by the pressure support and disposed in cooperative relation to the lower belt, and rollers carried by the pressure support and engaging the lower run of the upper endless belt.

3. In a tobacco stemming machine, leaf stripping means, and leaf-feeding means arranged near and cooperating with the stripping means, said leaf-feeding means comprising a lower endless belt, rollers engaging the upper run of the lower endless belt to limit its downward movement, a vertically movable pressure support ar-

ranged near and above the lower belt, an upper endless belt carried by the pressure support and disposed in cooperative relation to the lower belt, and rollers carried by the vertically movable pressure support and engaging the lower run of the upper belt to limit its upward movement with relation to the pressure support.

4. In a tobacco stemming machine, leaf stripping means and leaf-feeding means arranged near and cooperating with the stripping means, said leaf-feeding means comprising a lower endless belt, rollers arranged beneath and engaging the upper run of the lower belt, a pivotally mounted pressure support arranged near and above the lower belt to move vertically with relation thereto, an upper endless belt carried by the pressure support and disposed in cooperative relation to the lower belt, and rollers carried by the pressure support and arranged above and engaging the lower run of the upper belt.

5. In a tobacco stemming machine, leaf stripping means, and leaf-feeding means arranged near and cooperating with the stripping means, said leaf-feeding means comprising a lower endless belt, rollers arranged beneath the upper run of the lower belt to limit its downward movement, a support arranged near and above the lower belt, an upper endless belt carried by the support and disposed in cooperative relation to the lower belt, and rollers arranged above the lower run of the upper belt to limit its upward movement.

6. In a tobacco stemming machine, a pair of endless devices arranged side by side in spaced relation and having spaced stripping brushes, each brush being shorter than its endless device, said brushes having wire bristles, means for supporting the endless devices with approximately no overlap between the bristles of cooperating brushes at the point of contact with the leaf so that they strip the leaf from the stem without unduly destroying the stem, means to drive the endless devices in unison so that the brushes are brought together in proper order, and leaf-feeding means operating near the intake ends of the endless devices.

7. In a tobacco stemming machine, a pair of endless devices arranged side by side in spaced relation and having spaced stripping brushes, each brush being shorter than its endless device, means to drive the endless devices so that the brushes are brought together in proper order, and continuously moving leaf-feeding means arranged near the intake ends of the endless devices to supply the leaves to the same and also serving to positively hold the leaves from moving longitudinally in the direction of travel of the endless devices.

8. In a tobacco stemming machine, a fixed support, an endless structure having its upper run traveling over the fixed support and held thereby against downward flexing movement, spaced brushes carried by the endless structure, a swinging support pivotally supported near one end so that its opposite end may be adjusted different distances from the fixed support, an endless structure carried by the swinging support, spaced brushes carried by the last-named endless structure, and means to drive the endless structures in unison so that the brushes of the two sets are brought together.

9. In a tobacco stemming machine, a fixed support, an endless structure having its upper run traveling over the fixed support and held thereby against downward flexing movement, spaced brushes carried by the endless structure, a swing-

- ing support pivotally supported near one end so that its opposite end may be adjusted different distances from the fixed support, an endless structure carried by the swinging support, spaced brushes carried by the last-named endless structure, a swinging pressure element pivotally connected with the swinging support near the end of such swinging support which is remote from the pivotal support of the same, said pressure element engaging above the lower run of the upper endless structure to adjust such run with relation to the fixed support, means to drive the endless structures in unison, and leaf-feeding means operating near the intake ends of the endless structures. 10
10. In a tobacco stemming machine, a lower endless structure having a generally horizontal upper run, a swinging support pivotally supported near the discharge end of the lower endless structure and arranged above the lower endless structure, the free end of the swinging support being arranged near the intake end of the lower endless structure, an upper endless structure carried by the swinging support and having a lower run, a pressure element arranged above the lower run of the upper endless structure and pivotally connected at one end with the swinging support near the free end of such swinging support, means to raise and lower the opposite end of the pressure element, spaced brushes carried by the endless structures, means to drive the endless structures in unison, and leaf-feeding means arranged near the intake ends of the endless structures. 20
20. 11. In a tobacco steaming machine, a lower endless structure having a generally horizontal upper run, a swinging support arranged above such upper run and having its free end arranged near the intake end of the lower endless structure, means to adjust the swinging support to vary the distance between its free end and said upper run, an upper endless structure carried by the swinging support and having a lower run, an angularly adjustable pressure element carried by the swinging support and arranged above the lower run to force the same downwardly, stripping elements carried by the endless structures and spaced longitudinally of the same, means to drive the endless structures in unison, and leaf-feeding means operating near the intake ends of the endless structures. 25
25. 12. In a tobacco stemming machine, a lower endless structure having a generally horizontal upper run, an angularly adjustable support arranged near and above the upper run, an upper endless structure carried by the angularly adjustable support, a pressure element arranged above the lower run of the upper endless structure and angularly adjustable with relation to the angularly adjustable support, spaced stripping elements carried by the endless structures, means to drive the endless structures, and leaf-feeding means operating near the intake ends of the endless structures. 30
30. 13. In a tobacco stemming machine, a lower endless structure having a generally horizontal upper run, a support arranged near and above the upper run, means for vertically adjusting a portion of the support with relation to the upper run, an upper endless structure having a lower run and carried by the support, a pressure element carried by the support and arranged above the lower run to force the same downwardly, means for vertically adjusting a portion of the pressure element with relation to the support, spaced stripping elements carried by the endless structures, means to drive the endless structures, and leaf-feeding means arranged near the intake ends of the endless structures. 35
35. 14. In a tobacco stemming machine, a lower endless structure having a generally horizontal upper run, a support arranged near and above the upper run and extending longitudinally thereof, means to angularly adjust the support with relation to the upper run, an endless structure carried by the support and having a lower run, a pressure plate mounted upon the support and extending longitudinally of the same above the lower run, means to angularly adjust the pressure plate with relation to the support, spaced stripping elements carried by the endless structures, means to drive the endless structures in unison, and feeding means operating near the intake ends of the endless structures and embodying upper and lower endless structures. 40
40. 15. In a tobacco stemming machine, a lower endless structure having a generally horizontal upper run, a support arranged near and above the upper run, an endless structure carried by the support and embodying a lower run, an adjustable pressure element carried by the support and coacting with the lower run, an adjustable tension regulating device carried by the support and engaging the upper endless structure, spaced brushes carried by the endless structures, a rotary brush arranged to engage with the brushes of the upper endless structure to clean the same, means driven by the tension regulating means for driving the rotary brush, means to clean the brushes of the lower endless structure, means to drive the endless structures, and leaf-feeding means operating near the intake ends of the endless structures. 45
45. 16. In a tobacco stemming machine, a lower endless structure having a generally horizontal upper run, an adjustable support arranged near and above the upper run, an endless structure carried by the support and embodying a lower run, an adjustable tension regulating device carried by the upper support and engaging the upper endless structure, spaced brushes carried by the endless structures, a rotary brush mounted upon the adjustable support and arranged for engagement with the brushes of the upper endless structure, means driven by the tension regulating means for driving the rotary brush means to clean the brushes of the lower endless structure, means to drive the endless structures, and leaf-feeding means operating near the intake ends of the endless structures. 50
50. 17. In a tobacco stemming machine, spaced superposed endless structures, stripping brushes carried thereby and spaced longitudinally of the same, adjustable tension regulating devices for the endless structures, rotary brushes arranged to engage with the stripping brushes of the endless structures to clean the same, means driven by the tension regulating devices for driving the rotary brushes, means to drive the endless structures, and leaf-feeding means for the endless structures. 55
55. 18. In a tobacco stemming machine, in combination, an angularly adjustable support, an endless structure carried thereby, leaf-stripping elements carried by the endless structure, an adjustable pressure element carried by the adjustable support and engaging the endless structure, 60

- an adjustable tension regulating device carried by the support and embodying a rotatable element driven by the endless structure, a rotary brush carried by the support and arranged for engagement with the leaf-stripping elements between the same, and driving means between the rotary brush and the rotary element. 5
19. In a tobacco stemming machine, leaf-feeding means comprising a lower endless belt having an upper run, rollers disposed beneath the upper run for supporting said upper run, a vertically adjustable pressure support arranged near and above the lower belt, an upper endless belt carried by the pressure support and having a lower run extending beneath the pressure support and co-acting with the upper run of the lower belt, and rollers carried by the pressure support for coaction with the lower run of the upper belt. 10
20. In a tobacco stemming machine, leaf stripping means and leaf-feeding means arranged near and cooperating with the stripping means, said leaf-feeding means comprising a lower endless belt having an upper run, rollers coacting with the upper run to limit its downward movement, a vertically adjustable pressure support arranged near and above the lower belt, an upper endless belt carried by the pressure support and having a lower run, and rollers carried by the pressure support and coacting with the lower run to limit its upward movement with relation to the pressure support. 15
21. In a tobacco stemming machine, stripping means, and leaf-feeding means arranged near and cooperating with the stripping means, said leaf feeding means comprising a pair of endless structures arranged in superposed relation, and guide means for the adjacent runs of the endless structures including endless roller carrying elements. 25
22. In a tobacco stemming machine, stripping means, and leaf-feeding means arranged near the stripping means, such feeding means comprising a pair of endless structures arranged in superposed relation for affording adjacent runs, endless roller carrying elements arranged within the endless structures to engage with the adjacent runs, and guide elements engaging the runs of the endless roller carrying elements. 30
23. In a tobacco stemming machine, leaf-stripping mechanism, and leaf-feeding means for the same, comprising a pair of superposed endless plate belts having lateral extensions, flexible belts carried by the endless plate belts, a pair of grooved pulleys for each endless plate belt, each pulley embodying sets of sprocket teeth for engagement with the lateral extensions, an endless roller carrying element arranged within each plate belt and operating within the grooves of the pulleys, and guide members engaging the inner runs of the endless roller carrying elements. 35
24. In a tobacco stemming machine, leaf-stripping mechanism and leaf-feeding means for the same, comprising a pair of superposed endless plate belts, each plate belt comprising a plurality of plates, means pivotally connecting the plates, rollers carried by the pivotal means, flexible belts carried by the endless plate belts, a pair of grooved pulleys for each endless plate belt, each pulley embodying sets of sprocket teeth for engagement with the rollers, an endless roller carrying element arranged within each endless plate belt and operating within the grooves of the pulleys, and guide members having grooves for receiving the inner runs of the endless roller carrying elements. 40
25. In a tobacco stemming machine, leaf-stripping mechanism, and leaf-feeding means for the same, comprising a pair of superposed endless plate belts, each plate belt comprising a plurality of rigid pivotally connected plates, each plate having a pair of transverse grooves, extensions carried by the plate belts, flexible belts extending longitudinally of each endless plate belt and arranged within said grooves, a pair of grooved pulleys for each endless plate belt, each pulley embodying sets of sprocket teeth for engagement with the extensions, an endless roller carrying element arranged within each endless plate belt and operating within the grooves of the pulleys, and guide members having grooves for receiving the inner runs of the endless roller carrying elements. 45
26. In a tobacco stemming machine, leaf-stripping mechanism, and leaf-feeding means for the same, comprising a pair of superposed endless plate belts, each plate belt comprising a plurality of pivotally connected plates having extensions, flexible belts carried by the superposed endless plate belts with the flexible belt of the lower endless plate belt extending beyond an end of the same for a substantial distance, a pulley engaging the outer end of this flexible belt, a pair of grooved pulleys for each endless plate belt, each pulley embodying sets of sprocket teeth for engagement with the extensions, an endless roller carrying element arranged within each endless plate belt and operating within the grooves of the pulleys, and pressure guides having grooves for receiving the inner runs of the endless roller carrying elements. 50
27. In a tobacco stemming machine, leaf-stripping mechanism, and leaf-feeding means for the same, comprising a pair of superposed endless plate belts, each plate belt embodying a plurality of pivotally connected rigid plates, each plate having a transverse groove, a compressible rubber endless belt extending about the upper endless plate belt and held within the plate grooves, a flexible endless belt extending about the lower endless plate belt and held within the plate grooves of the same, and means to drive at least one endless plate belt. 55
28. In a tobacco stemming machine, leaf-stripping means embodying a pair of endless devices, leaf-feeding means for the leaf-stripping means, and leaf-scoring means arranged near the leaf-feeding means to engage with the leaves held therein. 60
29. In a tobacco stemming machine, leaf-stripping mechanism, leaf-feeding means therefor including a pair of superimposed endless structures, and leaf-scoring mechanism arranged near the endless structures to engage with the leaves held therein. 65
30. In a tobacco stemming machine, leaf-stripping mechanism, leaf-feeding means therefor, and a pair of superposed leaf-scoring devices arranged to engage with the leaves above and below the same while they are being advanced by the leaf-feeding means. 70
31. In a tobacco stemming machine, butt stemming mechanism embodying a pair of superposed endless devices, leaf-feeding means operating transversely of the intake ends of the superposed endless devices and embodying a pair of superposed endless structures, leaf-scoring means arranged near the superposed endless structures to engage with the leaves being advanced by the leaf-feeding means, a second leaf-feeding means receiving the leaves from the first-named leaf- 75

feeding mechanism and embodying superposed endless structures, and stripping mechanism disposed upon one side of the second-named leaf-feeding mechanism and embodying a pair of superposed endless devices.

32. In a tobacco stemming machine, stripping mechanism embodying an endless structure, transverse bars carried by the endless structure, a brush for each bar embodying a back and wire 10 teeth, the back being arranged upon the bar, and side members secured to the bar and arranged for clamping engagement with the back, the arrangement being such that the back may be readily removed from the bar.

33. In a tobacco stemming machine, a pair of endless devices arranged side by side in spaced relation and having spaced stripping brushes, each brush being shorter than its endless device, said brushes embodying yieldable wire bristles having 20 free end portions which are inclined in a direction opposite to the direction of travel of the brushes, means to drive the endless devices in unison so that the brushes are brought together in proper order, and leaf feeding means operating near the intake ends of the endless devices.

34. In a tobacco stemming machine, leaf stripping means comprising a pair of endless belts having stripping brushes each stripping brush being shorter than its endless belt and having 30 bristles, each brush having a stripping movement lengthwise of the leaf and throughout the major portion of the length thereof.

35. In a tobacco stemming machine, leaf stripping means comprising a pair of endless belts having stripping brushes, each stripping brush being shorter than its endless belt and having flexible bristles, each brush having a stripping movement lengthwise of the leaf and throughout the major portion of the length thereof, and means to drive 40 the belts so that their stripping brushes are brought together.

36. In a tobacco stemming machine, leaf stripping means comprising one or more pairs of superimposed endless belts having stripping brushes, each stripping brush being shorter than its endless belt and having flexible bristles arranged for engagement with the lamina of the leaf to strip the same from the stem, and means to drive the belts so that their stripping brushes are brought together on opposite sides of the leaf for simultaneous action thereon and movement lengthwise of the major portion thereof to strip the lamina from the stem.

37. In a tobacco stemming machine, leaf stripping means comprising one or more pairs of superimposed endless belts having stripping brushes, each stripping brush being shorter than its endless belt and having flexible bristles arranged for engagement with the lamina of the leaf to strip the same from the stem, and means to drive the belts so that their stripping brushes are brought together on opposite sides of the leaf for simultaneous action thereon and movement lengthwise of the major portion thereof to strip the lamina from the stem, and means for feeding leaves continuously to and through said stripping means and holding the stems against lengthwise movement during said stripping action.

38. In a tobacco stemming machine, leaf-stripping means comprising a pair of endless devices arranged side by side in spaced relation and having spaced stripping brushes, each brush being shorter than its endless device, said brushes having wire bristles, means for supporting the endless devices with approximately no overlap be-

tween the bristles of cooperating brushes at the point of contact with the leaf so that they strip the lamina from the stem without unduly destroying the stem, and means to drive the endless devices in unison so that the brushes are brought together in proper order.

39. In a tobacco stemming machine, superimposed endless devices, stripping means carried thereby, tension regulating devices for the endless devices, rotary cleaning elements arranged to engage with the stripping means of the endless devices to clean the same, and means driven by the tension regulating devices for driving the cleaning elements.

40. In a tobacco stemming machine, leaf stripping means comprising superimposed endless devices carrying spaced stripping brushes having wire bristles, means for driving the endless devices in unison so that the brushes are brought together in cooperative relation on opposite sides of a leaf, and means supporting the endless devices and guiding the movement of the brushes with the bristles of cooperating brushes approximately slightly spaced apart without substantial overlap of the bristles of the cooperating brushes so that they strip the lamina from the stem without unduly destroying the stem.

41. In a tobacco stemming machine, leaf stripping means comprising superimposed pairs of endless devices arranged side by side in spaced relation and carrying spaced stripping brushes having wire bristles, each brush being shorter than its endless device, means for driving the endless devices in unison so that the brushes are brought together in cooperative relation on opposite sides of a leaf, and means supporting the endless devices and guiding the movement of the brushes with the bristles of cooperating brushes slightly spaced apart lengthwise without substantial overlap of the bristles of cooperating brushes so that they strip the lamina from the stem without unduly destroying the stem.

42. In a tobacco stemming machine, leaf stripping means comprising superimposed pairs of endless devices arranged side by side in spaced relation and carrying spaced stripping brushes having wire bristles, each brush being shorter than its endless device, means for driving the endless devices in unison so that the brushes are brought together in cooperative relation on opposite sides of a leaf, and means supporting the endless devices and guiding the movement of the brushes with the bristles of cooperating brushes slightly spaced apart lengthwise without substantial overlap of the bristles of cooperating brushes so that they strip the lamina from the stem without unduly destroying the stem, and means for adjusting said supporting and grinding means to vary the distance between the bristles of cooperating brushes.

43. In a tobacco stemming machine, the combination of leaf feeding means, and leaf stripping means comprising a pair of endless devices having stripping brushes, each stripping brush being shorter than its endless device, means supporting and guiding the endless devices with the paths of movement of the cooperating brushes overlapping the major portion of the length of the leaf so that each brush has a stripping movement lengthwise of the leaf and throughout the major portion of the length thereof, and means for driving the endless devices so that the brushes are brought together on opposite sides of the leaf.
